Patented Apr. 5, 1966

204,231

SHOE HEEL ORNAMENT

Kaylor L. Glasgow, 3237 S. Forest St., and Karoly Bordy,
614 14th St., both of Denver, Colo.

Filed May 6, 1965, Ser. No. 85,148

Term of patent 3½ years

(Cl. D7—6)

FIG. 1 is a rear perspective view of a shoe heel ornament showing our new design;

FIG. 2 is a side elevational view thereof, the broken line showing of a shoe being for purposes of illustration only;

FIG. 3 is an enlarged front elevational view of the design shown in FIG. 1; and

FIG. 4 is a side elevational view thereof.

We claim:

The ornamental design for a shoe heel ornament, as shown and described.
